ORNAMENTAL METALWORK PANEL

Herman Harris Carter, Dallas, Tex.

Application February 12, 1959, Serial No. 54,571

Term of patent 14 years

(Cl. D54—2)

Figure 1 is a front elevational view of an ornamental metalwork panel, showing my new design, the rear thereof being the same; and

Figure 2 is a side elevational of the panel.

I claim:

The ornamental design for an ornamental metalwork panel, substantially as shown and described.
